(57) **CLAIM**

The ornamental design for a watch, as shown and described.

DESCRIPTION

FIG. 1 is a top view of a watch of my present design;

FIG. 2 is a bottom view thereof;

FIG. 3 is a left side view thereof;

FIG. 4 is a right side view thereof;

FIG. 5 is a rear view thereof;

FIG. 6 is a front view thereof;

FIG. 7 is a top right perspective view thereof, and,

FIG. 8 is a bottom left perspective view thereof.

The broken lines illustrate portions of the watch that form no part of the claim.

The surface hatching shown in FIGS. 1 and 7 is intended delineate the surface character and contour rather than a surface pattern.
